UNITED STATES PATENT OFFICE.

HENRY BECHTEL AND LOUIS FRITZ, OF PHILADELPHIA, PENNSYLVANIA.

SIGNAL FOR STEAM-BOILERS.

SPECIFICATION forming part of Letters Patent No. 601,699, dated April 5, 1898.

Application filed October 21, 1897. Serial No. 655,924. (No model.)

To all whom it may concern:

Be it known that we, HENRY BECHTEL and LOUIS FRITZ, citizens of the United States, residing at Philadelphia, in the county of 5 Philadelphia and State of Pennsylvania, have invented new and useful Improvements in Signals for Steam-Boilers, of which the following is a specification.

The object of our invention is to provide a 10 simple, efficient, and reliable device which is adapted for use as a "low-water" or "high-water" signal.

The invention consists of a device comprising a casing containing a horizontally-disposed expansion-rod, a right-angular lever hinged to the inside of the casing and connected with its short arm to said expansion-rod, while the other or long arm is attached to a valve-stem located in a valve-body communicating with a whistle.

Our invention further consists of the improvements hereinafter more fully described, and pointed out in the claims.

The invention will be more fully understood taken in connection with the accompanying drawings, forming part thereof, and in which—

Figure 1 is an elevation of our improved device adapted for use as a low-water signal 30 and showing the casing, the horizontally-disposed expansion-rod, the right-angular lever with its connection, and a whistle. Fig. 2 is a section on the line 2 2 of Fig. 1. Fig. 3 is an elevation similar to that shown in Fig. 1, 35 with the exception that the position of the hinge-point of the right-angular lever is changed, adapting the device to be used as a high-water signal; and Fig. 4 is an end view showing an adjusting device for the said expansion-rod.

Referring now to the drawings for a further description of our invention, A is a casing, of cast-iron or other metal, forming a chamber a. This chamber communicates with the inside 45 of the boiler B and is secured to the shell thereof by means of the nipple b, screwed into the lower try-cock hole if the device illustrated in Fig. 1 is to be used as a low-water signal, and in the upper try-cock hole 50 if the device illustrated in Fig. 3 is to be used as a high-water signal. The try-cock b'

is attached to the outer side of the device, as shown, while a blow-off valve b² is located at the bottom of the device.

The casing A, forming the chamber a, is 55 made of two pieces, the body a' and lid a². The latter is secured to the former by bolts a³. The lid a² is provided with an extension a⁴, having an aperture and valve-seat a⁵, and a whistle a⁶ is screwed or otherwise attached 60 to the said extension a⁴.

In the low-water signal shown in Fig. 1 a projection c is formed on the inside of the lid a², to which a right-angular lever c' is hinged at c². An expansion-rod d is connected at d' 65 with the short arm c³ of the right-angular lever c', while the long arm c⁴ of the said lever extends horizontally to the right and is connected with a valve-stem c⁵, fitted to the valve-seat a⁵. The expansion-rod d is, as before 70 mentioned, disposed horizontally in the chamber a in order that when the water in the boiler falls below the same or the low-water mark the entire rod is at once exposed to the steam and expands on account of the greater 75 heat it is subjected to. Through the expansion of the rod d the valve-stem c⁵ is actuated by means of the right-angular lever c' to admit steam to the whistle a⁶ to give a signal that the water has reached the low-water 80 mark.

The expansion-rod d may be attached with one end to the casing A, the other end being, as before stated, pivoted at d' to the right-angular lever c'; but preference is given to 85 an adjustable connection, (shown in Figs. 1 and 4,) because the various members of the device can be set better and so as that the valve-stem c⁵ is pressed snugly against the valve-seat a⁵ when the expansion-rod d is 90 subjected to a low temperature. This adjustable connection comprises the threaded nipple a⁷ of the casing A, through which the threaded end of the expansion-rod d protrudes. A nut d' is fitted onto the threaded 95 end of the rod d, and by turning the same in one or the other direction the valve-stem c⁵ can be set to the valve-seat a⁵, as desired. A jam-nut a⁸ is screwed onto the nipple a⁷ to secure the nut d', which latter is slotted, so that 100 a screw-driver may be inserted through the hole in the jam-nut a⁸ after the latter has

been loosened and the nut d' be turned to effect the proper adjustment of the valve-stem c^5 to the valve-seat a^5 .

The construction of the high-water signal shown in Fig. 3 is the same as that shown in Fig. 1 of the low-water signal, with the exception that the right-angular lever c' is hinged at c^5 and the connection of the expansion-rod d to the short arm c^3 of the lever c' is made 10 at d^3 in order that when the water rises in the boiler and the horizontal expansion or in this case the contraction rod is entirely at once immersed in the water, and thereby subjected to a lower temperature than it has 15 been when surrounded by steam, the rod d is contracted and operates, by means of the right-angular lever c' , the valve-stem c^5 to admit steam to the whistle to give a signal that the water has reached the high-water mark.

20 We are aware that signals have been provided having expansion or contraction tubes in which the water or steam circulates and which are arranged to actuate a valve to cause signals to be given; but as these tubes are 25 surrounded by the atmosphere they are not efficient and reliable, as will be understood by those skilled in the art to which our invention pertains.

Having thus fully described the nature and 30 objects of our invention, what we claim as new, and desire to secure by Letters Patent, is—

35 1. A signal for steam-boilers comprising a casing in communication with the boiler, a valve-seat formed with said casing, a whistle attached to said valve-seat, a right-angular lever located inside the casing and hinged to a projection thereof, a horizontally-disposed expansion-rod located inside the casing and

having one of its ends secured to the said 40 casing and the other to one arm of the said lever, and a valve-stem fitting the said valve-seat and being connected to the other arm of the said lever, substantially as and for the purposes set forth. 45

2. A signal for steam-boilers comprising a casing in communication with the boiler, a valve-seat and a whistle connected with said casing, a right-angular lever located inside the casing and hinged to a projection thereof, 50 a horizontally-disposed expansion-rod located inside the casing and having one of its ends adjustably secured to the said casing and the other to one arm of the said lever, and a valve-stem fitting the said valve-seat 55 and being connected to the other arm of the said lever, substantially as and for the purposes set forth.

3. In a signal for steam-boilers, the combination with a casing, a valve-seat, a valve- 60 stem, a lever and a horizontally-disposed expansion-rod located within said casing and having one end pivoted to said lever and the other end threaded and protruding from the said casing, of means for adjusting the said 65 rod and valve-stem, comprising a nipple on said casing, a nut on said threaded end of the expansion-rod, and a jam-nut screwing over the said nipple, substantially as and for the purposes set forth. 70

In witness whereof we have hereunto set our signatures in the presence of two subscribing witnesses.

HENRY BECHTEL.
LOUIS FRITZ.
